UNITED STATES PATENT OFFICE

1,930,300

DISPLAY CONTAINER

Edward H. Ball, Chicago, Ill., assignor to Chicago
Belting Company, Chicago, Ill., a corporation
of Delaware

Application November 11, 1931. Serial No. 574,382

12 Claims. (Cl. 206—65)

My invention relates to an improvement in displaying or dispensing packages and to a method of forming such packages, or of packing the articles to be displayed or dispensed. One object 5 is the provision of such a package which shall be quickly and easily made. Another object is the provision of a package which shall display the articles to be dispensed and shall permit the inspection of the articles from the exterior of 10 the package. Another object is the provision of a package which shall be adapted for the display and the dispensing of articles which may be removed one or more at a time from the package while leaving the package intact and permitting 15 the user or purchaser to determine, without opening the package, how many articles remain within the package. Another object is the provision of an improved method for packing articles. Other objects will appear from time to time in 20 the course of the specification and claims.

I illustrate my invention more or less diagrammatically in the accompanying drawings, wherein—

Figure 1 is a side elevation of a package;

25 Figure 2 is a longitudinal section through the package of Figure 1;

Figure 3 is a section on the line 3—3 of Figure 1;

Figure 4 is a longitudinal section similar to 30 Figure 2 through a variant form of package;

Figure 5 is a section on the line 5—5 of Figure 4;

Figure 6 is a perspective view of a third form of package;

35 Figure 7 is a longitudinal axial section of a package shown in Figure 6;

Figure 8 is a section on the line 8—8 of Figure 7; and

Figure 9 is a perspective view of a device adapted for the employment in forming the packages herein illustrated.

Like parts are indicated by like symbols throughout the specification and drawings.

Referring to the figures, A generally indicates 45 the articles nested in the package, each such member A including, for example, an annular flat flange A¹ and a cylindrical annulus A² formed integrally therewith with a beveled edge A³. A⁴ indicates a central or axial aperture in the ring 50 A¹. It will be understood that whereas I have shown a specific type of article adapted to be nested in the packages herein shown, I do not wish to be limited to the employment of my package or method with any particular article.

55 It is desirable, but not necessary, that the articles

packed may be formed to nest or inter-penetrates in order to add to the lateral or transverse stability of the package, and a nesting relationship is shown in the sectional views of Figures 2, 4 and 7.

B indicates a wrapping, herein shown as transparent, which may be in the form of a sheet or single layer wrapped about the nested articles. The edges may be lapped together, as at B¹ in Figure 3, to form a locking seam adapted to permit a measure of expansion or contraction, or the edges may be merely lapped one over another, as at B² in Figure 5. In either case the ends of the cylindrical closures so formed are inturned as at B³ to penetrate in the top and bottom of the tube or cylinder formed by the nested articles. Preferably the portions B³ are thrust sufficiently tightly into the ends of the package so formed to have a locking effect, not only upon the overlapping edges B¹ or B², but upon the articles 60 nested within the package. In effect they are locked together as a unit, and unless the user actually withdraws the ends B³ the package will remain tight. The covering B is preferably transparent. This is desirable, not only to permit the display of the goods, which may be of slight appearance or of some characteristic distinguishing color, but it is also advantageous to permit the user, after the withdrawal of one or more of the articles, to be able to tell how 65 many of the articles remain in the package.

I have illustrated in Figure 2 a package in which the nesting of the articles, in connection with the locking or securing effect of the inturned ends of the cover B, is sufficient to hold the 70 package compact. Where packages are likely to be exposed to rough usage, or where articles of larger size are packed, or where the articles do not readily nest, I find it desirable to employ an inner guiding or positioning means or reinforcement. I may employ, for example, a cylindrical tube C as shown in Figures 7 and 8. Or, I may employ an overlapped or rolled sheet as at C¹ in Figure 5, one edge of which may overlie the other as at C². If relatively flexible but springier material is used, such as a suitable stiff paper or fibre, a sheet of the right length may be rolled into the form in which it is shown in Figure 5 to a diameter somewhat smaller than the diameter of the apertures in the articles A. It may be 75 then inserted through said central apertures and released. The spring or expansion of the material will then cause it to take the position in which it is shown in section in Figure 5. Such a cylinder has an advantage over the cylinder C 80

of Figure 8 in that a sheet of a given size may be employed with various sizes of articles or apertures.

While under some circumstances merely in turning the ends of the cover B, as at B³ in Figure 2, may be sufficient to hold the package tight, I find it, under many circumstances, desirable to employ some sealing or protecting means. I may, for example, employ discs or seals D as shown at the opposite ends of the package in Figure 4. They may be pasted or otherwise secured to the ends of the package, and serve not only to close the ends of the package, but to hold the in turned portions B³ from escape and to hold the cover B tightly folded in place.

If greater protection or rigidity is required, particularly as when the packages are likely to be relatively roughly handled, I may employ closure caps E as shown in Figures 6 and 7. These may be frictionally fitted to the ends of the package, or they may be glued or cemented in place.

In order to mark the package or the goods I may employ any suitable label G. Such a label may be applied to the exterior of the cover B, or it may be positioned therewithin. It will also be understood that the cover B itself may be provided with any suitable markings formed in or applied to the substance thereof.

It will be realized that whereas I have described and shown a practical and operative device, nevertheless many changes may be made in size, shape, number and disposition of parts and in the materials employed, without departing from the spirit of my invention. I wish my description and drawings, therefore, to be taken as in a broad sense illustrative, rather than as limiting me to the particular showing or description herein.

The use and operation of my invention are as follows:

I have illustrated my invention in connection with leather pump packings, an article which may be dispensed in a hollow tube or cylindrical container. When so dispensed they are invisible to the prospective purchaser. Many articles, for example such as pump packings, are staples which are not ordinarily featured or positioned in a prominent position in a store. The unsightly fibre tube or container is commonly put on a shelf and it is only when a user actually asks for a pump packing that the salesman looks on the shelf for a package, finds the cylinder and shakes a packing out of it. He cannot tell from the exterior of the cylinder how many packings there are in a given package without removing them from the package and counting them. The present package is advantageous to the salesman and alluring to the purchaser. I may, for example, color the articles dispensed with a characteristic and striking color or design. This design is visible through the transparent covering B and calls to the prospective purchaser's attention the nature of the goods. For example, in a general store a farmer seeing such a container on the counter is reminded of a present or prospective need for one or more pump packings and makes a purchase. The salesman, when asked for a pump packing, can instantly see whether or not a given package contains a pump packing and how many packings remain in the package. It has been my experience that the employment of a package made in accordance with the drawings and description herein substantially increases the sale of the articles dispensed.

Any suitable substance may be employed for

the covering B, such as cellophane, oiled paper or the like. The covering may be entirely transparent or substantially transparent, or transparent only in part. The essential is that some or all of its area may be sufficiently transparent to permit an observer to see what articles are within the package and how many.

In the preparation of the package, I may employ a rolling device or base illustrated as J in Figure 9 and including flat top portions J¹ separated by a depression J² semi-cylindrical in contour. As an example of a method for forming the package in question, I may lay a sheet of the covering B on the tops J¹, a portion of it penetrating the aperture J². Before or after positioning the sheet in place, I may stack or align a series of the articles to be packed. I may employ the aperture J² to stack or align them. I may then insert in the aperture one of the cylinders C or C¹, if a cylinder is to be used. Then the sheet B is wrapped about the package, the edges being lapped as at B¹ or B². The ends are then turned in as at B³. Thereafter, if a sealing member is to be employed, I may apply the seals D or the caps E at one or both ends of the package. The label G may be applied before or after the application of the cover B, depending upon whether it is to be positioned internally or exteriorly of the cover. The packages so formed are slightly and convenient to handle, are easily assembled or packed and are tight and will stand rough handling.

I claim:

1. A package including a plurality of nested articles, such articles having central apertures, and a wrapper, at least in part transparent, rolled about said articles, the ends of said wrapper being inturned into the apertures of the articles situated at the ends of the package so formed.

2. A package including a plurality of nested articles, such articles having central apertures, and a wrapper, at least in part transparent, rolled about said articles, the ends of said wrapper being inturned into the apertures of the articles situated at the ends of the package so formed, the opposed edges of the wrapper being folded in inter-locking relationship.

3. A package including a plurality of nested articles, such articles having central apertures, and a wrapper, at least in part transparent, rolled about said articles, the ends of said wrapper being inturned into the apertures of the articles situated at the ends of the package so formed, and additional means for preventing the escape of the wrapper ends.

4. A package including a plurality of nested articles, such articles having central apertures, and a wrapper, at least in part transparent, rolled about said articles, the ends of said wrapper being inturned into the apertures of the articles situated at the ends of the package so formed, and additional means for preventing the escape of the wrapper ends, including seals applied to the package ends.

5. A package including a plurality of nested articles, such articles having central apertures, and a wrapper, at least in part transparent, rolled about said articles, the ends of said wrapper being inturned into the apertures of the articles situated at the ends of the package so formed, and additional means for preventing the escape of the wrapper ends, including caps applied to and surrounding the package ends.

6. A package including a plurality of nested

- articles, such articles having central apertures, and a wrapper, at least in part transparent, rolled about said articles, the ends of said wrapper being inturned into the apertures of the articles 5 situated at the ends of the package so formed, and an aligning tube positioned within the package and extending through the apertures of the articles therewithin. 7. A package including a plurality of nested 10 articles, such articles having central apertures, and a wrapper, at least in part transparent, rolled about said articles, the ends of said wrapper being inturned into the apertures of the articles situated at the ends of the package so formed, 15 and an aligning tube positioned within the package and extending through the apertures of the articles therewithin, said tube being formed of a sheet of yieldable material having overlapping edges. 20 8. A package including an internal aligning member, a plurality of apertured interpenetrating articles threaded upon said member, the length of the member being substantially the same as the total length of the articles aligned 25 therewith, and a wrapper surrounding said articles, said wrapper being at least in part transparent, and means for holding said wrapper in position about said articles. 9. A package including an internal aligning 30 member, a plurality of apertured interpenetrating articles threaded upon said member, the length of the member being substantially the same as the total length of the articles aligned therewith, and a wrapper surrounding said articles, said wrapper being at least in part transparent, and means for holding said wrapper in 35 position about said articles, including sealing members at the ends of the articles, the ends of the wrapper adjacent said sealing members being inturned to penetrate the ends of the aligning member. 40
10. A package including an internal aligning member, a plurality of apertured interpenetrating articles threaded upon said member, the length of the member being substantially the same as the total length of the articles aligned therewith, and a wrapper surrounding said articles, said wrapper being at least in part transparent, and means for holding said wrapper in position about said articles, including caps at the ends of the articles, the ends of the wrapper adjacent said caps being inturned to penetrate the ends of the aligning member. 80
11. The method of packaging apertured articles which includes threading upon an inner aligning means a sufficient number of said members to provide a stack of members equivalent in length to the length of said inner aligning means, thereafter positioning said stack upon a sheet of flexible transparent material, rolling said sheet about the stack with edges of said sheet overlapping, turning in the ends of the rolled sheet within the apertures at the ends of the stack of articles, and applying sealing means to the ends of the package. 90
12. A package which includes a plurality of nested interpenetrating articles, each such article having a central aperture, and a wrapper, at least in part transparent, rolled about said articles, the ends of said wrapper being inturned into the apertures of the articles situated at the ends of the package so formed, the wrapper being sufficiently tightly applied to prevent longitudinal relative movement of the nested articles and to prevent lateral displacement of adjacent articles in relation to each other, and means for 105 maintaining the wrapper tight enough to hold the articles in position. 100
